UNITED STATES PATENT OFFICE

WILLIAM B. JUPP, OF BROOKLYN, NEW YORK, ASSIGNOR TO INTERNATIONAL MOTOR COMPANY, OF NEW YORK, N. Y., A CORPORATION OF DELAWARE

THROTTLE-CONTROLLING MEANS FOR INTERNAL-COMBUSTION ENGINES

Application filed August 19, 1927. Serial No. 214,126.

The present invention relates to automatic controlling devices for the throttles of internal combustion engines and applies particularly where the engine is used in conjunction with electrical units for service in vehicles operating through an electric drive.

In a service of this character, where the engine is operated completely through electrical instrumentalities and all manual controls are eliminated, it is extremely desirable to reduce the number of control wires to a minimum to avoid too great a complexity of connections and adjustments as well as make the control cable as small as possible.

In view of the above considerations, an object of the present invention is to provide a throttle control which affords a greater number of throttle adjustments than there are control wires by means of mechanical interconnections which are actuated by means of suitable devices which operate individually or collectively at the instance of a current impulse through the appropriate control wires.

A further object of the invention is to combine a heat and spark control with a throttle control of the above character, thus further eliminating control wires and simplifying the mechanical and electrical construction, in addition to simplifying the operation of the engine.

Further and other objects of the invention will appear as the description proceeds and reference will now be had to the accompanying drawings forming a part hereof for a more detailed description of the invention, wherein:

Figure 1 is a side elevation of an internal combustion engine upon which the controlling means is carried.

Figure 2 is a plan view looking down upon the housing which carries the control means.

Figure 3 is a diagrammatic illustration showing the successive positions to which the link f^6 is moved upon proper energization of the magnets.

Referring particularly to Figure 1, a indicates an internal combustion engine of any desired form carried upon frame b and having a throttle connection c , a heater valve d and a spark lever e .

Upon the frame b is secured a U-shaped housing f having an upwardly extending portion f' with spaced parallel walls to carry a rock shaft f^2 . Suitable operating means f^3 , such as electromagnets, or air valves operated by electromagnets, are secured to the bridge of the U-shaped bracket f . An arm f^4 connects the armatures f^5 , or other means actuated by f^3 , and connected to the arm at a point away from the center thereof is a link f^6 . This link is connected to a crank arm f^7 which is securely mounted on rock shaft f^2 .

Upon the rock shaft f^2 , are mounted crank arms c' , d' and e' , these arms being connected to their respective control means in the following manner. A link c^2 is connected to a crank arm c^3 which is mounted upon the throttle control shaft of the throttle c . A similar link d^2 is connected with a crank arm d^3 which is carried with the heater valve d and in this manner the throttle and heater valve are operated simultaneously by the controlling device carried upon the U-shaped bracket. A link e^2 is connected to a crank arm e^3 which is carried upon a transversely extending rock shaft e^4 and a link e^5 , connected to another crank arm on rock shaft e^4 extends longitudinally of the engine and operates through a linkage e^6 and a spark controlling arm e .

It will be apparent that the spark lever e is controlled simultaneously with the heat and throttle valve.

In operation, the link f^6 will be moved downwardly through three successive stages, thus affording four positions to which the throttle may be moved. Upon energization of the right hand magnet the link f^6 will be moved from the position in which it is shown in the top view of Figure 3 to the position shown in the second view of Figure 3.

Upon deenergization of the right hand magnet and energization of the left hand magnet, the link f^6 will be moved from the second position in Figure 3 to the third. Upon energization of both magnets simultaneously, the link f^6 will be brought to the position shown in the lowest illustration of Figure 3.

The energization of the magnets in the proper sequence is effected by means of the switch and connections shown in Figure 1.

From the above description it will be seen that this invention combines in a single mechanism the means for controlling, automatically, not only the throttle but also the heater valve and the spark lever. The mechanism is of simple construction and capable of being applied, or removed, with great facility.

What I claim is:

- 10 1. In a controlling mechanism for the throttle, heat and spark of an internal combustion engine, a pair of actuating means, a U-shaped bracket secured to the engine structure, means to secure the actuating means to the bridge of the U-shaped bracket, an arm connected between the actuating means, an extension to the bracket forming opposed sides, means to journal a rock shaft in the sides, a crank on the shaft, means connecting the crank with the arm at a point nearer one of the actuating means than the other, a plurality of operating cranks on the shaft, means connecting the cranks to the throttle, heat and spark controls respectively, and means to effect the actuation of the actuating means in a desired order.
- 15 2. In a controlling mechanism, a plurality of actuating means, a floating arm connected to the means, a shaft, means to connect the arm with the shaft at a point nearer one of the actuating means than the other, and means to effect the actuation of the actuating means individually and simultaneously.
- 20 3. A throttle control for operating a throttle in a predetermined number of successive stages comprising a plurality of actuating means, floating means interconnecting the actuating means, means to connect the interconnecting means with the throttle control at a point on the interconnecting means a greater distance from one actuating means than another, and selective electrical means to effect the actuation of the actuating means individually and simultaneously.
- 25 4. This specification signed this 17th day of August, A. D. 1927.

WILLIAM B. JUPP.
